UNITED STATES PATENT OFFICE

138,644

DESIGN FOR A CABLE TENSION REGULATOR

John W. Cade, La Canada, Calif., assignor to
Sturgess, Inc., Glendale, Calif., a corporation
of California

Application May 23, 1944, Serial No. 113,718

Term of patent 14 years

(Cl. D52—1)

To all whom it may concern:

Be it known that I, John W. Cade; a citizen
of the United States and a resident of the city
of La Canada, county of Los Angeles, State of
California, have invented a new, original, and
ornamental Design for a Cable Tension Regu-
lator, of which the following is a specification,
reference being had to the accompanying draw-
ing, forming a part thereof.

Fig. 1 is a perspective view of a cable tension
regulator showing my new design.

Fig. 2 is a view somewhat enlarged from Fig.
1, and showing a straight side view of the reg-
ulator.

Fig. 3 is an end view of Fig. 2.

The far side of the regulator, not seen in the
drawing, is substantially the same as the side
shown.

I claim:

The ornamental design for a cable tension reg-
ulator, substantially as shown and described.

JOHN W. CADE.
